UNITED STATES PATENT OFFICE.

ROBERT A. KIRKPATRICK, OF TORONTO, ONTARIO, CANADA.

MALT-HOUSE.

1,176,297.

Specification of Letters Patent. Patented Mar. 21, 1916.

Application filed January 22, 1915. Serial No. 3,733.

To all whom it may concern:

Be it known that I, ROBERT A. KIRKPATRICK, a citizen of the United States, residing at Toronto, in the Province of Ontario, in the Dominion of Canada, have invented a new and useful Improvement in Malt-Houses, of which the following is a specification.

This invention relates to the construction of malt houses or buildings for carrying on the manufacture of malt, and more particularly to malt houses of the kind in which the germinating or growing of the malt and the drying can be accomplished in the same chambers without changing the grain or malt from one floor or chamber to another, and in which the malting and drying or different stages of these treatments can be in progress simultaneously in different chambers of the house.

The objects of this invention are to construct a malt house of this character in which the passages or ducts for the moist air and the air for drying the malt are so arranged relative to the malting and drying chambers as to greatly reduce the space usually required for the same, thus reducing the size and the cost of construction of a malt house of given capacity, while nevertheless permitting the required different treatments of the material in the several chambers in such a manner as to insure the production of the malt in the most expeditious and economical manner; also to so construct a malt house that the air for drying the malt in one or more chambers after most of the moisture has been removed therefrom can be used again in another chamber or chambers in connection with the drying of some of the moister malt.

In the accompanying drawings, consisting of five sheets: Figure 1 is a longitudinal sectional elevation of a malt house embodying the invention, on line 1—1, Fig. 3. Fig. 2 is a fragmentary sectional elevation thereof on line 2—2, Fig. 5. Fig. 3 is a sectional plan view thereof on line 3—3, Fig. 1. Fig. 4 is a fragmentary sectional elevation thereof on line 4—4, Fig. 3. Fig. 5 is a sectional plan view thereof on line 5—5, Fig. 1. Fig. 6 is a fragmentary transverse sectional elevation thereof on line 6—6, Fig. 1. Fig. 7 is a transverse sectional elevation thereof on line 7—7, Fig. 1. Fig. 8 is a transverse sectional elevation thereof on line 8—8, Fig. 1. Fig. 9 is a fragmentary sectional plan

view thereof on line 9—9, Fig. 1. Fig. 10 is a fragmentary longitudinal sectional elevation thereof on line 10—10, Fig. 5. Fig. 11 is a fragmentary transverse sectional elevation thereof on line 11—11, Fig. 1. Fig. 12 is a transverse sectional elevation thereof on line 12—12, Fig. 1.

A represents the malt house or building, which, in the construction shown, is of rectangular plan. The building has two internal walls or partitions B B' which divide the building into two longitudinal portions in which the malting and drying chambers are located and between which passages for conducting dry or heated air and moist air to the chambers are located. Floors C C' C² connect the partition walls with the outside walls of the building, the intermediate floor C' and the partitions B B' dividing the building into four malting and drying compartments or chambers 1, 2, 3 and 4. The number of chambers depends upon the desired size and capacity of the house. Each of the chambers is provided with the usual perforated malting and drying floor D arranged above the floors C' C² of the chambers and on which the malt rests.

E represents a humidifier, which may be of any desired type or construction and which provides moist or humidified air for the malting operation. The humidifier shown includes a plurality of tempering coils e which are adapted to modify the temperature of air conducted to the humidifier from the exterior of the building through the air inlet e', a plurality of spray nozzle for spraying water into the current of air, and eliminators of usual construction for removing free particles or drops of water from the humidified air. The humidified air passes from the humidifier to vertical conduits e² e², from which it is distributed to the malting and drying chambers.

The hot air for drying the malt may be supplied from any suitable source, such as furnaces F F which, as shown, are located in the front portion of the building and from which the hot air passes through flues f f to the main upright hot air supply passage f' f'. The air fed to the chambers can be brought to any desired drying temperature by admitting more or less air from the exterior of the building through ducts f² f² if the air from the furnaces is too hot, the admission of outside air being controlled by dampers or valves f³. In case the air outside

the building is warm so that not much heat need be added to it, a heater F', comprising a number of heating coils between which the incoming air flows, may be used. The furnaces, heaters and humidifier may be of any suitable construction and may be located in any desired part of the building provided that the hot and the humidified air is supplied to opposite ends of the building.

10 The space between the partition walls B B' is divided by a vertical wall g and by a plurality of walls or floors g', connecting the vertical wall g and the partition walls B B', into a plurality of conduits or passages for the air. In the construction shown, H H and H' H' represent passages or conduits connecting with the upright moist air conduits e² e² and through which the moist air flows respectively to the upper and lower 15 malting chambers, the passages H H H' H' being provided with a plurality of openings h controlled by dampers or valves h' from which the moist air flows through passages h² below the floors C C'. These passages are 20 open at one side so that the air can flow into the malting and drying chambers. I I and I' I' represent corresponding passages connecting with the main hot air supply passages f' f' and through which the hot or drying air flows respectively to the upper and lower 25 chambers through openings i in the passages which are controlled by dampers or valves i'. The passages H H H' H' and I I I' I' converge or taper in opposite directions, the large ends of the passages H H H' H' connecting with and receiving the moist air from the conduits e² at one end of the building, while the large ends of the passages I I I' I' connect with and receive the hot air 30 from the hot air supply passages f' f' at the other end of the building. By thus alternately arranging the moist air and hot air passages, the large end of one passage will be adjacent to the small end of the other 35 passage, and the passages are nested or interlocked so that a considerable saving in space is effected. The tapered shape of the passages is also desirable because the air is withdrawn from the passages into the malting and drying chambers through the discharge openings located at intervals lengthwise thereof, so that as the quantity of air in a passage decreases, the cross sectional area thereof also decreases, and a more uniform 40 distribution of the air throughout the length of the malting and drying chambers is thus insured.

45 The moist and hot air enters the chambers near the upper portions thereof and is withdrawn from the malting and drying chambers through exhaust ducts K arranged lengthwise of the chambers adjacent to the outer walls of the building and communicating with the chambers by means of openings k below the perforated floors D, the air

being thus caused to pass downwardly through the perforated malting floors D and the malt thereon. The exhaust ducts on each side of the house are connected by upright passages k' at the front end of the house, or the end opposite to that from which the moist air is supplied, which connect with a transverse passage k² leading to a moist air exhaust fan L located in the front portion of the building

75 The efficiency of operation of the malt house can be increased by using the air, which has been employed in the final stages of drying the malt in one chamber, for the initial drying of malt in another chamber, 80 since the air contains but little moisture after passing through the nearly dry malt in the last stages of drying. This can be accomplished as follows: L' L² represent two exhaust fans, one of these fans being located at each side of the building, and each fan is adapted to exhaust dry air from either of the two chambers on its side of the building. Each fan is connected with the adjacent exhaust ducts K by means of a 85 transverse passage k³ leading to the eye of the fan, and an upright passage k⁴ connecting the two ducts K located on the same side of the building. The ducts K are provided at opposite ends with valves or doors k⁵ which 90 can be set so as to permit either the moist air fan L or one of the hot air fans L' or L² to exhaust air therefrom. Each of the hot air fans L' L² is provided with a discharge passage l through which air can be discharged to the outside of the building, and an exhaust passage l' from which the air is discharged to a transverse return air passage l² located near the rear end of the building. Dampers or valves l³ serve to 95 direct the air from the hot air fans either into the passage l or into the passage l'. The return air passage l² communicates with a central return air duct M extending 100 lengthwise of the building between the walls B B' and communicating with both the hot air supply flues f' f', doors or valves m and m' controlling the flow of the return air to the flues f' f'. These doors make it possible to control the admission of return air to the 105 hot air flues f' f' and to mix the return air with air admitted from the exterior or from the furnaces or heater so as to properly temper as required the mixed air. By means of 110 this arrangement one of the hot air fans can be used for withdrawing air from a chamber on one side of the building in which the malt is in the final stages of drying, and returning the air to the return duct M from 115 which it passes to one of the hot air flues f' and to a chamber at the other side of the building in which the malt is in the initial stages of drying. From this chamber the air is withdrawn by the other hot air fan 120 and is discharged outside of the building. 125

In the operation of the malt house, one chamber after another is charged in such a manner that when the malt reaches the final drying stage in a chamber on one side of the house, the chamber containing malt which is in the initial drying stage will be located at the opposite side of the house. The moist air fan L is also provided with a valve or damper n whereby the air with-
5 drawn from the malting chambers can be either discharged from the building or passed into a return passage N leading to the humidifier, so that the moist air can be circulated and used repeatedly with or without the addition of fresh air from the exterior of the building as conditions may permit.
10
15

O represents the usual steeping tank in which the grain is soaked in water prior to 20 the passing of the same into the malting chambers.

The malt house described is adapted to be used for treating the malt in any desired manner, and the malt in any of the chambers can be subjected to any desired conditions of heat or humidity. By means of the construction described, a decided saving is also effected in the cost of construction of a malt house of given capacity, owing to the 25 compact arrangement of the air passages within the same. The cost of operating the malt house is also reduced by this construction, which enables the drying air to be used more than once in the process of making 30 malt.
35

The building shown has only four malting chambers, but it will be readily understood that malt houses embodying the invention may be provided with as many 40 chambers as desired and that the capacity of the building may be increased by adding to the number of stories or by adding other chambers at the sides of those shown. The building may be constructed of any desired 45 material, the walls of the hot and moist air passages being, however, made of material which will resist the flow of heat through the same.

I claim as my invention:
50 1. In a malt house, the combination with a malting chamber, of passages for moist air and drying air extending lengthwise of said chamber and communicating along their sides with said chamber, said moist air 55 passage receiving the moist air at one end of the chamber and said drying air passage receiving the drying air at the other end of the chamber, means at one end of said passages for supplying moist air to the moist 60 air passage, means at the other end of said passages for supplying drying air to the drying air passage, and means for exhausting air from said chamber.
65

2. In a malt house, the combination of a malting chamber, an inclosed space of sub-

stantially uniform rectangular cross-section extending along one side of said chamber, a wall dividing said space into two tapering passages, the larger end of one of said passages being adjacent to one end of the chamber and adapted to receive moist air, and the larger end of the other passage being adjacent to the other end of the chamber and adapted to receive drying air, and discharge openings in said passages for discharging 75 air into the chamber.
70

3. In a malt house, the combination with a malting chamber, of passages for moist air and drying air extending lengthwise of said chamber and adapted to conduct air to said 80 chamber, said moist air passage receiving the moist air at one end of the chamber and said drying air passage receiving the drying air at the other end of the chamber, said passages decreasing in cross-sectional 85 area from their receiving ends to their other ends and being arranged with the large end of one passage adjacent to the small end of the other passage.

4. In a malt house, the combination with a malting chamber, of passages for moist air and drying air extending along one side of said chamber and communicating along their sides with said chamber, means for supplying moist air to one of said passages 95 at one end of said chamber, and means for supplying drying air to said other passage at the opposite end of said chamber.
90

5. In a malt house, the combination with a malting chamber, of passages for moist air 100 and drying air extending along one side of said chamber and communicating along their sides with said chamber, said passages decreasing in cross-sectional area in opposite directions, means for supplying moist air to 105 the large end of one of said passages, and means for supplying drying air to the large end of said other passage.

6. In a malt house, the combination of a malting chamber, passages for moist air and 110 drying air located one above the other at one side of said chamber, said passages being tapering and arranged with the larger end of one passage adjacent to the smaller end of the other passage and having discharge openings arranged at intervals in 115 said passages, and means for admitting air to the larger ends of said passages.

7. In a malt house, the combination of a plurality of superimposed malting chambers, 120 an upright tier of passages for moist air and drying air arranged at one side of said chambers, one moist air passage and one drying air passage being provided for each chamber, said moist air passages receiving 125 air from one end of the house, and said drying air passages receiving air from the other end of said house, said moist and drying air passages being alternately arranged.
130

8. In a malt house, the combination of a

- plurality of superimposed malting chambers, an upright tier of passages for moist air and drying air arranged at one side of said chambers, one moist air passage and one drying air passage being provided for each chamber, said moist air passages receiving air from one end of the house, and said drying air passages receiving air from the other end of said house, said moist and drying air passages being alternately arranged and tapering from their receiving to their opposite ends.
9. In a malt house, the combination of a plurality of superimposed malting chambers, passages for moist air and drying air arranged at one side of said chambers, said passages being tapering and arranged with the larger end of one passage adjacent to the smaller end of the adjacent passage, means connecting the larger ends of the passages at one end of the chambers for admitting drying air thereto, and means connecting the larger ends of the other passages at the other end of the chambers for admitting moist air thereto, and discharge openings spaced at intervals in said passages.
10. In a malt house, the combination of a plurality of malting chambers, vertical partition walls separating said chambers into upright tiers, moist air passages and drying air passages arranged between said partition walls and conducting air to said chambers, said moist air passages receiving air from one end of the house, and said drying air passages receiving air from the other end of said house, said moist and drying air passages being alternately arranged and tapering from their receiving to their opposite ends.
11. In a malt house, the combination with two parallel malting chambers, moist air and drying air passages for each chamber extending substantially horizontally lengthwise between said chambers, said moist and drying air passages for one chamber being arranged one over the other adjacent to said chamber and communicating along its sides therewith, and the moist and drying air passages for the other chamber being arranged one over the other adjacent to said other chamber and communicating along its sides with said other chamber, means at one end of said house for supplying moist air to said moist air passages, and means at the other end of the house for supplying drying air to said drying air passages.
12. In a malt house, the combination of a pair of malting chambers arranged side by side, passages for each of said chambers for supplying moist and drying air thereto, said passages extending lengthwise of the chambers in the space between the chambers, said moist air and said drying air passages de-
- creasing in cross-sectional area in opposite directions, and means for supplying moist air and drying air to the large ends of said passages.
13. In a malt house, the combination of a plurality of malting chambers, an air passage leading to each of said chambers, exhaust passages having openings connecting with said chambers, means for discharging air from said chambers through said exhaust passages, and a return passage connecting with said discharging means and said air passages for admitting air discharged from one of said chambers to another chamber.
14. In a malt house, the combination of a plurality of malting chambers, air passages leading to said chambers for conducting air into said chambers, exhaust passages connecting with said chambers, an exhaust device connected with one of said exhaust passages for withdrawing air from one of said chambers, a return passage connecting with said exhaust device, and connecting with the air passage for another chamber, and an exhaust device for withdrawing the air from said other chamber.
15. In a malt house, the combination with a plurality of malting chambers, air passages for admitting drying air to said chambers, air feed ducts at one end of the house for feeding drying air to said passages, means at the other end of said house for discharging air from one of said malting chambers, and a passage extending lengthwise of said house and connecting said discharging means and said air feed ducts for passing said drying air from said discharging means to the feed duct of another malting chamber, and means for discharging the air from said other chamber.
16. In a malt house, the combination of a plurality of malting chambers, air passages leading to said chambers for admitting air thereto and extending lengthwise of said chambers at one side thereof, exhaust ducts extending lengthwise of said chambers at the other side thereof and communicating with said chambers, means for withdrawing air from the exhaust duct of one of said malting chambers, a return passage arranged below said air passages and adapted to be connected with said air withdrawing means and with the air passage for another malting chamber, and means for withdrawing air from said other chamber.

Witness my hand, this 21st day of January, 1915.
